HAIR SPRAY SHIELD

Nancy E. Reeves, 15727 Faculty Ave.,
Bellflower, Calif. 90706

Filed Sept. 4, 1973, Ser. No. 394,384

Term of patent 7 years

Int. Cl. D28—03

U.S. Cl. D86—10 A

FIG. 1 is a top plan view of a hair spray shield showing my new design, the opposite side of the shield being the same;

FIG. 2 is an elevational view from one side edge;

FIG. 3 is an elevational view from the other side edge;

FIG. 4 is a bottom edge view; and

FIG. 5 is a top edge view.

I claim:

The ornamental design for a hair spray shield, substantially as shown.
